(57) **CLAIM**

The ornamental design for an air freshening device, as shown and described.

DESCRIPTION

The nature of this product is as a dispenser employed as an air freshener system.

FIG. 1 is a left, front perspective view of an air freshening device embodying our new design;

FIG. 2 is a front elevational view thereof;

FIG. 3 is a top plan view thereof;

FIG. 4 is a bottom plan view thereof;

FIG. 5 is a left side elevational view thereof, the right side elevational view thereof being a mirror image of the left side shown;

FIG. 6 is a rear elevational view thereof;

FIG. 7 is a left front elevational view of a second embodiment of an air freshening device embodying our new design; the front and rear elevational views thereof being the same as shown in FIGS. 2 and 6, respectively;

FIG. 8 is a top plan view thereof;

FIG. 9 is a bottom plan view thereof; and,

FIG. 10 is a left side elevational view thereof, the right side elevational view thereof being a mirror image of the left side shown.

The broken line representations of fragrance pads in FIGS. 1 and 7 are for illustrative purposes only and form no part of the claimed design.
